HARRY E. WOLFF, OF NEW YORK, N. Y.

AUTOMATIC LIGHTER.

1,106,175.

Specification of Letters Patent.

Patented Aug. 4, 1914.

Application filed November 13, 1912. Serial No. 731,188.

To all whom it may concern:

Be it known that I, HARRY E. WOLFF, a citizen of the United States, residing in the city of New York, in the county and State 5 of New York, have invented certain new and useful Improvements in Automatic Lighters, of which the following is a specification.

This invention in automatic lighters relates to that class of devices adapted to 10 instigate combustion through the agency of an active scintillating medium, coacting with an inflammable element in promoting the ignition of the latter. In devices of 15 this character, the invention has more particular reference to that type, wherein the ignition is effected by the abrasive frictional contact of a sparking material, as for example, ferro-cerium when rubbing, scraping, 20 or abrading against a rough surface, preferably, a hardened steel file of suitable form, in order to develop a shower of sparks and direct them upon a slow match or inflammable wick. In this connection, my in- 25 vention is directed to certain improvements in the instrumentalities for automatically actuating the sparking elements and for extinguishing the fire on the wick, as will be more fully hereinafter described.

30 Primarily the object of my present invention is to provide an improved automatic lighter in which the operation thereof may be facilitated to a greater extent than by similar devices in vogue and previous to 35 my invention in so far as I am at present aware, and further, to provide a construction conducive to endurance, fidelity in operation and ease in manipulation, together with simplicity in construction. The fea- 40 tures characteristic of my invention whereby I accomplish this object lie in the construction, as illustrated in the drawings hereto attached, which, when taken with the appended descriptive matter forms a part of 45 this specification, and the distinct features of novelty are more particularly referred to in the claims at the conclusion of the specification.

The chief feature of my improved automatic lighter is a tubular reservoir adapted 50 to contain a spirit combustible, disposed as a handle which carries the mechanism for the sparking instrumentalities, the taper or wick, the operating lever and the automatic snuffer for extinguishing the flame of

the wick. The operating lever and its co-ordination embraces a particular feature of my invention by virtue of which the sparking instrumentalities are set into action, while at the same time, the wick is uncovered by a simple manipulation, and upon releasing the lever, the flame is snuffed out and the wick chamber covered to prevent leakage of the spirit.

The invention is illustrated in the construction as depicted in the drawings in which:

Figure 1 is a side elevational view of my improved automatic lighter substantially full size, with the snuffer closed down upon 60 the wick and wick chamber. Fig. 2 is a rear elevational view of the upper part thereof with a portion of the actuating mechanism removed. Fig. 3 is an enlarged side elevational view partly taken in section of the 65 upper part of the lighter illustrating the actuating mechanism in a normal position or that as illustrated in Fig. 1, and Fig. 4 is a similar view to that of Fig. 3, showing the action of the sparking instrumentalities 70 and their coacting mechanism, in order to effect the ignition of the wick. In this view, the snuffer is shown in an elevated position whereby the free wick is exposed for use. Moreover, in this view, certain parts which 75 are shown in section in Fig. 3 are in full lines.

In the several figures, similar characters of reference are employed to designate like or the same parts where they occur, wherein, 80

1 depicts a spirit chamber or receptacle, composed preferably of metallic tubing, having an integral closed bottom. This is capped by a screw cover 2, threaded to the interior wall of the receptacle 1. The screw 85 cover 2 is composed of a similar material to that of the receptacle 1, and is formed with a dome 3 and a knurled flange 4, which makes a fluid tight connection with the corresponding end of the chamber 1 by the intervention of a gasket 5. The fluid chamber or receptacle 1 is charged with the burning fluid, preferably gasoline, benzine or the like and a quantity of absorbent cotton 6 containing the same.

Secured to and carried by the dome 3 is a standard 7, and penetrating the dome 3 and obliquely carried thereby in fluid tight relation therewith is a wick tube or burner 8 containing a wick 9, which extends down- 100 105 110

wardly into the chamber 1, and saturated absorbent cotton 6. The standard 7 is of rectangular tubular formation and is provided with lateral opposing integral disks 10, toward the upper extremity thereof, which are provided with outwardly projecting integral lugs 11, constituting stops.

At the upper extremity of the standard 7, and coaxially aligned therewith and of a similar form, is an integral igniter-block pocket 12. This is of smaller cross section than that of the standard 7 and is adapted to contain a small block of igniting metal and permit of a free up and down movement thereof; this pocket is provided with an integral bracket 13, to which is secured a pivoted snuffing cap 14, having a wick cap 15. The snuffer has a cam groove 16.

17 refers to the operating lever which is composed preferably of formed sheet metal and is provided with a pair of lugs or ears 18 pivoted to the standard 7 substantially intermediate of the length thereof and swung therefrom upon a pivot 19.

25 Housed within the operating lever 17 is a trigger or pawl 20 swinging on a stud 21 projected inwardly from and carried by one of the sides to wit; that nearest the observer as illustrated in dotted lines in Fig. 1. Said trigger appears in full lines in Figs. 3 and 4, where the side of the operating lever which carries it is removed to elucidate the mechanism housed by the said lever. The trigger 20 is provided with an incline 35 heel 22 backed to the wall of the lever 7 by a lug 23, projecting from the surface of the said wall and integral therewith. A spring 24 secured to the lever 17 presses against the trigger 20, in order to thrust the heel 22 against the lug 23.

50 Pivots secured to and housed by the lateral tubular walls of the standard 7 is a bell crank lever 25, provided with the arms 26 and 27; this is swung by the arm 27 upon a pivot 28 secured to the lateral walls of the standard 7, while the arm 26 is pivoted to an operating finger 29, by a stud 30. The arm 26 of the bell crank lever is provided with a slightly curved shoe 31 upon which 55 rests and thrusts the end of the trigger 20, when the lever 17 is in its normal position or that as indicated in Figs. 1 and 3. The standard 7, opposite the pivot 28 is perforated on one side for the reception of the wick tube 8 and on the opposite side for the introduction and free oscillating movement of the arm 27 of the bell crank lever 25. The finger 29 is bifurcated at its upper terminal to form a crotch or jaw 32, which 60 engages a plurality of studs 33. These are in the instance illustrated 6 in number and are integrally formed with and carried by a hub or disk 34 revolving on a stud 35 carried transversely and axially by the lateral walls of the standard 7. The disk 34 en-

gages a squared axle 36 carrying a circular serrated sparking wheel 37. This latter is of laminated construction, and comprises in the instance illustrated, three toothed disks, the teeth of which are formed preferably by a stamping or punching operation, and the disks are composed of a suitable grade of steel, after which they are hardened. The sparking wheel 37 is located between the lateral walls of the standard 7. The opposite end walls thereof are cleared away to permit of freedom of rotation of the said wheel. This is adapted to be driven in the direction indicated by the arrow.

38 refers to a block of sparking metal contained within the chamber 12, which is adapted to be spring pressed downwardly by an arm 39 of a spring 40, said arm passes through a slot 41 in the corresponding end wall of the pocket 12. The cap 14 swings upon a pivot 42 secured to a bracket 13 secured to the standard 7. The spring 40 is housed within the cap 14 and is coiled about the free portion of the pivot 42, secured to the standard 7.

90 Coiled about the pivot 19 is a spring 43, an arm 44 of which thrusts against one of the inner end walls of the standard 7, and opposite to that of the wick tube 8. Another arm 45 of the spring 43 has a rectangularly bent toe 46, which passes through and plays in a curved groove 47 in one of the lateral walls of the standard 7, where it enters into and is secured to the ear 18 of the lever 17. Coiled about the stud 28 is 100 a spring 48, having an arm 49 thrusting against a lug 50, carried by the arm 26 of the bell crank lever 25, and a second arm 51 thrusting against the wick tube 8. The effect of the said spring, while thus positioned, is to thrust the bell crank lever arm 26 upwardly while swinging upon the pivot 28 driving the finger 29 upwardly to engage one of the studs 33, and carry the sparking wheel 37 around in contact with the sparking metal 38, as will be more fully explained hereinafter. The finger 29 has an integral lug 52 which engages the bent end 53 of a torsional spring 54 coiled about the stud 50; said spring has its other end secured in 110 a cross-slot 55 in the stud 30. The spring 48 constitutes the main spring of the driving mechanism of the hub 34 and sparking wheel 37 and in the position of the finger 29 and bell crank lever 25, as illustrated in 120 Fig. 3, the said main spring thrusting against the lug 50, and wick tube 8 has driven the finger 29 upwardly to an extent sufficient to engage the crotch 32 of the finger 29 with the stud 33 of the hub 34 and 125 effect the rotation thereof and the driving of the sparking wheel 37 for a sixth of a revolution.

66 refers to the snuff cap lever, which is formed integral with the lever 17; it is pro-

vided with a pin 57 which plays in the cam groove 16 of the snuffing cap 14. Upon swinging the lever 17 upon its pivot 19, the lever 56 will swing the snuffing cap 14 upon its pivot 42, and uncover the wick tube 8. This is accomplished by pressing the lever 17 downwardly, when the said snuffing cap will assume the position indicated in Fig. 4. The trigger spring designated 24 is secured to one wall of the lever 17, which carries the trigger stud 21, the free end 59 of which bears against the trigger 20 and presses the inclined heel 22 thereof in a direction toward the lug 23. The upper edge of the igniter block pocket 12 has an integral lug 60, formed in the manner of a hook, under which is removably secured the free terminal of the spring 40.

The operation of my improved automatic lighter will be effected by swinging the lever 17 upon the pivot 19 in a direction toward the spirit chamber 1. This will cause the arm 56 to throw the snuffing cap upwardly on its pivot 42 and uncover the wick tube 8, while at the same time, upon continuing the movement, the end of the trigger 20 bearing downwardly on the curved shoe 31, while backed by the lug 23 against which the heel 22 rests, will carry the bell crank lever 25 and operating finger 29 downwardly against the action of the main spring 48 until the crotch 32 of the finger 29 is brought to a position of engagement with a stud 33 of the hub 34, when the end of the trigger 20 will be carried off from the end of the curved shoe 31, and the main spring 48 will be released, whereupon the bell crank lever 25 will be thrust upwardly and swinging upon its pivot 28 will drive the finger 29 to engage its crotch 32 against the engaging stud 33 of the hub 34 of the sparking wheel 37, and carry the latter around for one sixth of a revolution. Due to the downward pressure upon the sparking metal 38 by the arm 39 of the spring 40 against the serrations of the sparking wheel 37 while the latter is in rotation, a shower of sparks will be projected against the free end of the wick 9, resulting in the ignition thereof. The action of the bell crank lever 25 and operating finger 29 immediately prior to the release thereof from the trigger 20 when the lever 17 is depressed is fully illustrated in Fig. 4. Upon releasing the said lever, the spring 48 will drive the lug 18 and lever 17, around on the pivot 19 to a normal position or that indicated in Figs. 1 and 3, when the trigger 20 will be caused to assume a position in engagement with the curved shoe 31 of the bell-crank lever 25 where it will rest in the normal position as indicated in Fig. 3, and the snuffing cap 14 will be thrown down upon the standard 7 and the wick cap 15 brought into a position over the free end of the wick tube 8. This will cap the same

together with wick 9 and snuff out the flame which resulted from the previously described operation.

It will be observed by the above description of my improved automatic lighter that the effect of the lever 17 and its coördination with the bell crank lever 25, trigger 20 and operating finger 29 actuated through the instrumentality of the main spring 48 bears a resemblance to the trigger mechanism of self-cocking fire arms. In this connection the downward depression of the lever 17, cocks as it were, the operating finger 29, and releases it thereafter, whereby the wick 9 is ignited by a single movement being imparted to the operating lever 17. It will be further observed that the automatic action of the snuffing cap 14 is simultaneous with the operation of the lever 17, and while the lighter is being cocked and fired, its action is of an absolute automatic nature. Hence it will be understood that my improved lighter may be operated with the greatest of facility and ease in manipulation, and moreover that it is of durable and simple construction, and

Having fully described my invention, I claim as new and desire to secure by Letters Patent of the United States:—

1. An automatic lighter of the character described comprising, a spirit chamber, a standard carried thereby, a laminated sparking wheel carried by the standard, and a self-cocking trigger mechanism consisting of an operating lever, a bell crank lever pivoted to said standard, an operating finger pivoted to said bell crank lever, a trigger carried by said operating lever, and a main spring secured to said standard.

2. An automatic lighter of the character described comprising, a spirit chamber, a standard carried thereby, a wick tube secured to said chamber and extending laterally therefrom, an igniter block carried by the said standard, an operating lever pivoted to the standard, and a laminated sparking wheel pivoted to the standard intermediate the operating lever and said igniting block.

3. In an automatic lighter of the character described, a spirit chamber, a cap carried by said chamber and secured thereto, a wick tube and a standard carried by the cap, said wick tube projecting laterally from the standard, a laminated sparking wheel carried by said standard, an igniting block carried by the standard, an operating lever pivoted to the standard, a bell-crank lever pivoted to the standard, an operating finger pivoted to said bell-crank lever and adapted to impart rotary movement to said sparking wheel, and a self cocking trigger mechanism carried by the said operating mechanism.

4. In an automatic lighter of the character described, a spirit chamber, a standard carried thereby, a wick tube secured to said chamber and extending laterally therefrom,

an igniting block carried within the upper portion of the standard, an operating lever pivoted to said standard, a laminated sparking wheel pivoted to the said standard intermediate of said igniting block and operating lever, a bifurcated finger for operating said sparking wheel, a snuffer pivoted to the said standard, and an arm projecting from the operating lever and pivoted to the said snuffer whereby the snuffer is adapted to cover and uncover the wick tube by the operation of the lever.

5. In a lighter of the character described, a spirit chamber, a standard carried thereby, a wick tube secured to said chamber and projecting laterally therefrom, a sparking block carried within the upper portion of the standard, in combination with a snuffing cap pivoted to the standard, of an integral lock portion projecting over the upper portion 15 of the standard, and of a spring coiled around the pivot carrying the snuffing cap, one free end of said spring being engaged beneath said hook portion and the other free end adapted to contact with and depress the said sparking block.

20 6. An automatic lighter of the character described comprising, a spirit chamber, a

standard carried thereby, a wick tube secured to said chamber, a laminated sparking wheel 30 secured to said standard, a snuffing cap pivoted to the standard, a sparking block carried within the upper portion of the standard, an operating lever pivoted to said standard and having an integral upward projecting arm pivoted to said snuffing cap whereby the snuffing cap is adapted to cover and uncover the wick tube by the operation of said lever.

7. In a lighter of the character described, 40 a laminated sparking wheel.

8. In an automatic lighter of the character described, a laminated sparking wheel, in combination with a driving hub provided with a plurality of integral annularly situated and laterally projecting driving studs, 45 and a bifurcated operating finger for engaging said studs, substantially as described.

In testimony whereof I have signed my name to this specification in the presence of 50 two subscribing witnesses.

HARRY E. WOLFF.
